UNITED STATES PATENT OFFICE.

JOE WOOD MORRISON, OF PITTSBURGH, PENNSYLVANIA.

SCRAPER.

1,198,257.

Specification of Letters Patent. Patented Sept. 12, 1916.

Application filed February 5, 1916. Serial No. 76,425.

To all whom it may concern:

Be it known that I, JOE WOOD MORRISON, a citizen of the United States, and a resident of Pittsburgh, in the county of Allegheny and State of Pennsylvania, have invented a new and Improved Scraper, of which the following is a full, clear, and exact description.

This invention relates to brushing and scrubbing and has particular reference to such devices as are intended to be used in the cleansing of pots, pans or similar utensils.

Among the objects of the invention is to provide a simple and convenient appliance, for the purpose indicated, of relatively cheap but strong, substantial nature, one that adapts itself readily to the irregularities that may exist in the surface to be scraped or cleansed, one that is of a durable nature, and one of such a construction with reference to the handle portion that the material scraped will not be likely to come into contact with the operator's hand.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a side elevation, one end being in vertical section, showing a preferred embodiment of my invention; Fig. 2 is an end elevation; Fig. 3 is a transverse section on the line 3—3 of Fig. 1; and Fig. 4 is a perspective view of the bottom or active portion of the scraper.

Referring now more particularly to the drawings, I show a construction including a body or holder 10 made preferably of a block of wood or other suitable rigid material. To the upper side is secured a handle 11 of any suitable form and by any suitable means. The form of handle shown, however, adapts the device well for its purpose and insures that the hand of the operator will be kept well out of the way of the active scraping portion of the appliance.

The block constituting the body of the holder is preferably of substantially rectangular form on its bottom and is provided

with a plurality of longitudinal parallel grooves 12. The ends of the grooves extend fully to the ends of the body 10 and there merge into upwardly directed grooves 13 60 which extend upwardly along the ends of the block parallel to one another or in parallel vertical planes corresponding to the longitudinal grooves 12. At each end of the block is formed a horizontal groove 14 65 which, like the grooves 13, is comparatively shallow. This groove 14 at each end may be regarded as the terminus of the grooves 13 which merge into the same.

The cleansing or scraping element may 70 partake of various forms or constructions, but the form preferred by me comprises a single wire element of any suitable form in cross section. This element is shown as a whole at 15, and the manner of bending 75 it for fitting it to the body of the scraper may be described in detail as follows: Beginning at one end 16 the wire is fitted in one of the upwardly directed end grooves 13, and at a point spaced below the lower 80 surface of the body the wire is then bent sharply into a horizontal plane parallel to the bottom of the body forming a scraping element or long tooth 17. The wire is thence bent upwardly forming a loop 18 85 fitted into the groove 12. This manner of forming the teeth and loops may be repeated any desired number of times depending upon the length of the body of the scraper or other conditions and at the end of the same 90 groove the wire is bent upwardly with a rounded turn 19, the metal of the wire extending along the groove 13 at the opposite end of the same groove 12 from the starting point and there is formed a loop 20 95 which, in effect, interlocks in a pair of the grooves 13 and the cross groove 14 connected therewith. In other words, the loop 20 hooks around that portion 21 of the end 100 of the body bounded by the pair of adjacent grooves 13 and that portion of the transverse groove connecting the same. The wire is thence bent back parallel to the first series 105 of scraping elements 17 throughout the entire series of grooves, the other end of the wire having the same relation to the opposite end of the body as the first end of the wire has to the starting point. But for the fact that the points of the scraper at one end are bent on an acute angle and those on the 110 other end on a rounded angle the structure at both ends is practically the same, and a

description of either will be applicable to the other.

The loops 18 being wedged or forced otherwise into the slots 12 and the loops 5 20 being engaged over the end portions 21 of the body in the manner above set forth, the scraping device or series of tooth-like projections 17 is held in a secure manner along the body of the scraper. To make 10 the connection more secure, however, I preferably employ a binding plate 22 at each end of the body, the same being connected detachably to the body by means of screws 23 or their equivalent. These plates 22 are 15 clamped over the looped portions of the wires close to the ends of the loops. The lower corners or ends of the body 10 are also preferably formed in acute angles as viewed in side elevation, which, together 20 with the manner of forming the turns or corners of the scraping device, provides free access to the edges or corners of practically any utensil, such as pots, pans or the like, to be cleaned. Either the sharp corners or 25 the rounded corners of the scraping device may be projected into an irregular surface, according to the nature of each particular case. It will be noted also that the projections 17 of the scraping device are preferably of different lengths, and that as 30 viewed in side elevation they are arranged to break joints, or, in other words, so that there will be no gaps when the device is moved laterally.

35 I claim:—

1. In a scraper of the nature set forth, the combination of a holder having a plurality of parallel longitudinal grooves formed in its lower face, a one piece wire 40 bent to form a plurality of scraping projections fitted in said grooves, and means securing the ends of the wire to the ends of the holder.
2. In a scraper, the combination of a rigid body having a series of grooves in its lower surface, wire scraping elements having loops projecting into said grooves and having the end portions thereof extending upwardly along the ends of the holder, and 50 means to lock said upwardly projecting ends firmly to the ends of the holder.

3. A scraping device comprising a holder having a groove extending along its lower surface, and a wire scraper bent to form

upwardly projecting loops fitted into said 55 groove and having end portions bent to extend along the ends of the holder.

4. In a scraper, the combination of a rigid holder having a plurality of grooves formed in its bottom, wire scraping means 60 having upwardly projecting loops extending into said grooves and having end portions extending along the ends of the holder, and means positively holding the ends of the wire means in engagement with the ends 65 of the holder.

5. In a scraper, the combination of a rigid holder, wire scraping means having projections extending upwardly into the bottom of the holder and having end portions bent to coöperate with the end surfaces 70 of the holder, and means to make positive connection between the ends of the wire means and the ends of the holder.

6. In a scraper, the combination of a 75 rigid holder, wire scraping means having projections extending upwardly into the bottom of the holder and having end portions forming loops interlocking with the ends of the holder.

7. The combination with a rigid holder having a substantially rectangular flat bottom, of a wire scraping device bent to form a plurality of scraping portions lying in a plane parallel to but spaced below the bottom of the holder, portions of the wire between adjacent scraping portions being projected upwardly for engagement with the bottom of the holder, and said wire scraping device also including upwardly bent 90 end portions having loops locking over certain portions of the ends of the holder.

8. The combination with a holder having a flat bottom and ends having grooves arranged in parallel planes, said ends also 95 having transverse grooves with which the other end grooves communicate, of a wire scraping device having a plurality of projecting portions constituting scraping elements proper, said scraping projections being staggered and breaking joints as described and also having end portions bent upwardly forming loops lying in the up-right and transverse grooves.

JOE WOOD MORRISON.
